PAPER-FORMING MACHINE

Lloyd Hornbostel and Alonzo A. Neese, Beloit, Wis., assignors to Beloit Iron Works, Beloit, Wis., a corporation of Wisconsin

Application November 16, 1953, Serial No. 392,376

15 Claims. (Cl. 92—43)

This invention relates to a paper forming machine, and more particularly, to an improved cylinder paper machine of the type having cylinder molds rotating toward the same direction and positioned in line so as to successively deposit fibrous webs onto a pickup felt to obtain a multi-layer paper product.

Although cylinder type paper machines have been used to substantial extent in the paper machine art, particularly in the formation of multi-layer paper webs, there have been a number of difficulties encountered in satisfactory commercial operation of machines of this type. In general, the machines heretofore used involved a plurality of separate cylinder molds positioned in line so as to successively deposit fibrous webs upon a pickup felt running over the top of each of such cylinder molds. Unfortunately, there was very little flexibility afforded in the cooperation between each cylinder mold and the overrunning pickup felt, since the pickup felt must run in a line so as to engage the top portion of each of such cylinder molds for the purpose of removing the fibrous web therefrom. If, for example, it is desired to employ stocks having different properties as feed for certain of the cylinder molds, substantially no variation could be permitted in the cooperation between the pickup felt and the cylinder mold so as to effect a more preferred manner of picking up the various different fibrous webs formed on different cylinder molds. Moreover, any type of breakdown in one of the cylinder molds, necessarily resulted in the shutting down of the entire machine, because the pickup felt operated so as to engage the top peripheral portion of each of such cylinder molds. In addition, a certain maximum operating speed, in feet per minute of web formed, was permitted using the prior art cylinder mold structure, and this maximum speed was based upon the particular cooperation between the pickup felt and cylinder mold, whereby the pickup felt transferred the web from the cylinder mold surface.

These and other difficulties have been overcome by the present invention, which provides for a much more versatile pickup cooperation between the cylinder mold unit and the pickup felt, and which further provides for greater operating speeds and for longer continuous operation. These advantages are accomplished by the use of a looped forming wire in conjunction with the cylinder mold and a turning roll or lower couch roll within the loop of the forming wire for effectively adjusting the position of the forming wire for cooperation with the pickup felt and for moving the forming wire out of operating position, when the particular cylinder mold unit is to be taken out of operation, without shutting the entire machine down.

It is, therefore, an important object of the instant invention to provide an improved cylinder-type paper machine, having greater versatility of operation and being capable of longer continuous operation than heretofore achieved.

It is a further object of the instant invention to provide a cylinder type paper machine, comprising a plurality of separate looped forming wires, a cylinder mold within the loop of each of said forming wires for effecting fibrous web formation on the wire, a looped pickup felt having a felt run positioned above the upper run of

2

each of said forming wires to receive the fibrous web therefrom, and a turning roll within the loop of each of said forming wires for selectively directing the upper run of each wire against and away from the felt run to respectively permit and prevent web transfer from the wire to the felt.

Other and further objects, features and advantages of the instant invention will become apparent to those skilled in the art from the following detailed disclosure thereof and the attached drawings forming a part hereof, which show a preferred embodiment of the instant invention.

On the drawings:

Figure 1 is an elevational view, with parts shown diagrammatically and parts broken away, showing the cylinder type paper machine embodying the instant invention;

Figure 2 is a view in elevation showing the mounting arrangement for a cylinder mold employed in the instant invention, with parts shown diagrammatically;

Figure 3 is a view in elevation of the turning roll structure employed in the instant invention, with parts shown diagrammatically; and

Figure 4 is a view in elevation of the structural mounting for the cylinder mold and the associated turning roll arrangement employed in the instant invention.

As shown on the drawings:

In Figure 1, the reference numeral 10 indicates generally the forming section of a cylinder type paper machine embodying the instant invention, which comprises a plurality of separate looped forming wires 11a, 11b, 11c, 11d and 11e, a cylinder mold 12a, 12b, 12c, 12d and 12e within the loop of each of said forming wires 11a, 11b, 11c, 11d and 11e for effecting fibrous web formation on the wire associated with the mold; a looped pickup felt 13 having a felt run 13' positioned above the upper run of each of the forming wires 11a, 11b, 11c, 11d and 11e to receive the fibrous web therefrom; and a turning roll 14a, 14b, 14c, 14d and 14e within the loop of each of said forming wires for selectively directing the upper run of each wire against and away from the felt run 13' to respectively permit and prevent web transfer from the wire to the felt.

Referring now to certain details of the individual cylinder mold units, designated generally units a, b, c, d and e, respectively, it will be noted that there are here shown a total of five cylinder mold units; and the instant forming section 10 is designed to operate ordinarily employing only four of such units (to prepare a four-ply sheet of paper), with the fifth unit in standby condition or under repairs, as the case may be. With the fifth unit in standby condition (the standby unit here shown being the unit c), the instant forming section 10 may be operated continuously even though one of the operating cylinder mold units develops an operational defect. For example, if the unit d develops an operational defect, the standby unit c is put into operation and the unit d is taken out of operation, in each case by appropriate movement of the turning rolls 14c and 14d respectively (as well as the various other operations such as feeding stock which are connected with the starting up or shutting down of an individual cylinder mold unit).

Referring now to the details of an individual cylinder mold unit such as the first unit in line, unit a, it will be noted that this unit comprises a tank-like container 15a which encloses the operating elements such as the cylinder mold 12a, the forming wire 11a and the turning roll 14a. The tank 15a may function as here shown primarily as a guard for the other elements, or it might function as in the case of many cylinder mold units as the tank which retains the stock at a predetermined level and in which the cylinder mold 12a rotates so as to pick up a fibrous web on the surface thereof. As here shown, however, in the

instant arrangement it is preferable to employ a stock inlet 16a which feeds stock upwardly from beneath the operating floor F and against the uprunning side of the cylinder mold 12a. The fibrous web is thus formed within the region of the cylinder mold periphery that is fed by the stock stream from the stock inlet 16a and the cylinder mold 12a rotating as indicated by the arrow and carrying the forming wire 11a in the direction indicated develops a fibrous web upon the forming wire at the approach of the upper run 11a' of the forming wire 11a. The upper run 11a' of the forming wire thus continues over to the turning roll 14a, at which point the fibrous web is transferred from the forming wire 11a to the lower run 13' of the pickup felt 13. The forming wire 11a then is turned downwardly and around a second roll 17a, which is preferably mounted as a tensioning as well as a turning roll (and then back around the second roll 17a to the cylinder mold 12a). The turning roll 14a thus functions as a lower couch roll in effecting web transfer to the pickup felt 13. An upper couch roll 18a is positioned within the loop of the pickup felt 13 approximately above the turning roll 14a, and the upper couch roll 18a and the turning roll 14a cooperate to define a nip through which the web is passed between the felt 13 and the forming wire 11a, and at which the web is transferred from the forming wire 11a to the web 13. As will be shown hereinafter, both the upper couch roll 18a and the turning roll 14a are mounted so as to be adjusted in position and so as to correspondingly adjust the plane or angle of the nip formed therebetween in order to obtain a preferred nip arrangement for web transfer.

In connection with the means for supporting the various elements here provided, the primary structure is that of a frame indicated generally at 19 and having upright supporting portions 20 and 21 at opposite ends of the forming section 10 which are suitably affixed to the operating floor F and extend upwardly to a main cross or longitudinal support 22. A plurality of parallel drop legs 23a, 23b, 23c, etc. are provided for each of the units a, b, c, etc. and the drop legs 23a extend downwardly from the longitudinal support member 22 to merge with the side walls of the tank 15a to complete the overall frame structure 19. The movement of the individual upper couch roll 18a is provided for by a pivot arm 24a and adjustable locking device 25a. The pivot arm 24a mounts the upper couch roll 18a for rotation at one end of the arm and at the other end of the arm 24a it is pivotally secured to the drop leg 23a. The adjusting device 25a is secured to the middle of the pivot arm 24a and is adjustably mounted (as by the threaded engagement here shown) on the drop leg 23a, so that it may be moved upwardly and downwardly by rotation thereof to carry the pivot arm 24a upwardly and downwardly. The details of such a mounting arrangement will be well understood by those skilled in the art and need not be further discussed herein. It will be noted, however, that the upper couch roll 18a is swingably mounted on drop leg 23a of the frame 19 for limited adjustment.

The pickup felt 13 has the upper run thereof moving over a plurality of guide rolls 26 and the felt then is turned about a turning guide roll 27 mounted at the forward end of the tank 15a of the first unit a by suitable bearing means 28, and the lower run 13' of the felt 13 then passes from beneath the turning guide roll 27 to return in substantially a horizontal direction across the top of each of the cylinder mold units a, b, c, etc. and finally through a pair of guide and press rolls 29 and 30 positioned after the last cylinder mold unit e. The individual upper couch rolls 18a, 18b, etc. may each affect the travel of the lower pickup felt run 13' to a limited extent, in urging the felt run 13' against the individual forming wires 11a, 11b, etc. This movement is, however, relatively limited and it has not been used effectively to actually move a lower felt run against and away from an individual cylinder mold in a commercial operation. Instead, it has been found that the instant forming

wire 11a and turning roll 14a arrangement must be used to actually effect the operation of taking a cylinder mold out of operation or putting a cylinder mold into operation without interrupting continuous operation of the whole

5 forming section 10.

The interchange of one cylinder mold unit for another on the operating line is accomplished in accordance with the instant invention by the provision of means for adjusting the position of the turning roll 14a, 14b, etc. in each unit. The particular means provided will be described hereinafter, but the function of such means is that of dropping one turning roll, such as the turning roll 14c down below the lower pickup felt run 13' so as to avoid cooperation between the pickup felt 13' and the forming wire 11c; and raising another turning roll such as the roll 14a upwardly to effect cooperation between the forming wire 11a and the felt run 13'. As will be appreciated, the turning roll 14c as well as the lower roll 17c is a relatively large piece of equipment and the mechanism required for raising and lowering the rolls 14c and 17c may be relatively complex in nature, although the provision of such mechanism generally as here indicated will be fully understood by those skilled in the art from the instant disclosure. As shown in Figure 4, the back-side of the cylinder mold unit c may be provided with a frame member 31c suitably anchored to the floor F and presenting a pair of upright legs 32c and 33c which mount a crossbeam 34c. The crossbeam 34c and upright leg 33c have an arcuate track 35c suitably located therein to permit vertical as well as horizontal movement of a stub shaft 36c therein. As indicated in Figure 4, the stub shaft 36c has a yoke 37c clamped to the outer extremity thereof to hold the same against rotation, and the yoke 37c is in turn pivotally connected to the operating arm 38c of a hydraulic cylinder 39c pivotally connected to the floor F. Suitable actuation of the arm 38c causes the stub shaft 36c to slide in the arcuate track 35c, as will be readily understood by those skilled in the art. The yoke 37c may be used to hold the shaft 36c against rotation in a given position, or the yoke 37c may be released and reclamped upon the shaft 36c in order to hold the shaft 36c at a different angular position relative to the yoke 37c.

Referring now to Figure 3, which shows other features of the structure mounting the rolls 14c and 17c, it will be seen that the stub shaft 36c is formed at one end of a mounting bar 40c which extends the full length of the rolls 14c and 17c and which has mounted near opposite ends thereof frame members 41c and 42c which carry suitable bearings (not shown) for rotatably receiving the shaft 43c of the roll 14c and the shaft 44c of the roll 17c. The rolls 14c and 17c are thus carried on the mounting bar 40c, which in turn is moved upwardly and downwardly and horizontally in accordance with the movement of the stub shaft 36c thereof.

It will be appreciated, of course, that a stub shaft 55 corresponding to the stub shaft 36c could be mounted in a similar manner at the opposite end of the supporting bar 40c so as to provide support at both ends of this bar, and suitable hydraulic moving means, such as the cylinder 39c could be positioned so as to operate at both ends of the mounting bar 40c. However, it is particularly desirable to provide an arrangement whereby the mounting bar 40c (and the rolls 14c and 17c) are cantilevered at one end thereof, as shown in Figure 3. Such cantilever mounting will, of course, involve a very 60 sturdy structure on the part of the leg member 33c, as well as an anchoring or weighted portion 45c extending outwardly from the depending leg 33c and suitably fastened to the floor F, so as to balance the assembly. The structural details of a suitable cantilever mounting 65 of the type here shown, as well as the actual design of members of suitable strength and weight are well within the skill of those familiar with the art, and the instant drawings are primarily diagrammatical with respect to the showing of actual sizes of the elements.

The primary object of the instant disclosure is that of pointing out the superiority of a cantilever mounting for the rolls 14c and 17c as well as an adjustable mounting for those rolls (by movement of the stub shaft 36c in the arcuate track 35c). The cantilever mounting thus shown permits the removal of the forming wire 11c and the replacement thereof with another forming wire, when such is necessary during operation. During normal operation, as indicated, for example in connection with the unit e, the support member 42e suitably carries the rolls 14e and 17e and is supported by a bridging member 46e which is mounted on a flanged floor support 47e. When it is desired to take the cylinder mold unit out of service, however, the member 46e is unbolted from the flanged floor member 47e and the cross support member 42e and removed. After the leg member 46e has been removed, the rolls 14e and 17e are cantileverly supported, as indicated in connection with the unit c in Figure 3, and the entire assembly may be moved downwardly and toward the cylinder mold as indicated in the showing of the unit c in Figure 1. In Figure 3, the same position of the unit c is shown with the member 46c removed from the structure.

In like manner, as shown in Figure 2, the cylinder mold itself must be provided with a suitable cantilever support arrangement, so that the forming wire may also be removed from the cylinder mold at the same time it is removed from the rolls 14c and 17c. As shown in Figure 2, the cylinder mold 12c is suitably supported by bearings 48c and 49c, the bearing 48c being suitably mounted in the frame 31c (as shown in Figure 4) and being supported by the drop leg 32c and suitable anchoring means 50c affixed to the drop leg 32c and to the Floor F. The details of white water removal lines, etc., which would ordinarily be located within the hollow shaft 51c of the cylinder mold 12c which is supported in the bearing 48c are, of course, omitted for the purpose of simplifying the instant drawings. The stub shaft 52c at the opposite end of the cylinder mold 12c is supported by the bearing 49c, which is ordinarily supported by a bridging member (not shown, but indicated at the location 53e in the unit e). The bridging leg member is suitably supported on a flanged floor support 54c during ordinary operation, and this member is removed as shown in Figure 2 when it is desired to replace the forming wire.

Also the stock inlet 16c is suitably mounted, for example, on a track 55c to permit limited movement toward and away from the cylinder mold 12c, for moving the inlet 16c back to the position shown in unit c during the wire changing operation. Means are thus provided for separating all "outside" elements such as the inlet 16c from the outside of the forming wire loop and pulling together all "inside" elements from within the forming wire loop to permit replacement of the wire 11c, without interrupting the operation of the remaining cylinder mold units a, b, d and e.

It will be understood that modifications and variations may be effected without departing from the scope of the novel concepts of the present invention.

We claim as our invention:

1. A cylinder type paper machine, comprising a plurality of separate looped forming wires, a cylinder mold within the loop of each of said forming wires for effecting fibrous web formation on the wire, a looped pickup felt having a felt run positioned above the upper run of each of said forming wires to receive the fibrous web therefrom, and a turning roll within the loop of each of said forming wires for selectively directing the upper run of each wire against and away from the felt run to respectively permit and prevent web transfer from the wire to the felt.

2. A cylinder type paper machine, comprising a plurality of separate looped forming wires, a cylinder mold within the loop of each of said forming wires for effecting fibrous web formation on the wire, a looped pickup felt

having a felt run positioned above the upper run of each of said forming wires to receive the fibrous web therefrom, a turning roll within the loop of each of said forming wires, and means engaging each of said turning rolls to move each roll for selectively directing the upper run of each wire against and away from the felt run to respectively permit and prevent web transfer from the wire to the felt.

3. A cylinder type paper machine, comprising a plurality of separate looped forming wires, a cylinder mold within the loop of each of said forming wires for effecting fibrous web formation on the wire, a looped pickup felt having a felt run positioned above the upper run of each of said forming wires, a couch roll positioned above each of said forming wires and within the loop of each of said forming wires for directing the felt against each of said forming wires to receive the fibrous web therefrom, and a turning roll within the loop of each of said forming wires for selectively directing the upper run of each wire against and away from the felt run to respectively permit and prevent web transfer from the wire to the felt.

4. A cylinder type paper machine, comprising a plurality of separate looped forming wires, a cylinder mold within the loop of each of said forming wires for effecting fibrous web formation on the wire, a looped pickup felt having a felt run positioned above the upper run of each of said forming wires, a couch roll positioned above each of said forming wires and within the loop of each of said forming wires for directing the felt against each of said forming wires to receive the fibrous web therefrom, and a turning roll within the loop of each of said forming wires, and means engaging each of said turning rolls to move each roll for selectively directing the upper run of each wire against and away from the felt run to respectively permit and prevent web transfer from the wire to the felt.

5. A cylinder type paper machine, comprising a frame, a plurality of cylinder molds aligned within the frame, separate looped forming wires for each cylinder mold having the cylinder mold within the loop thereof for effecting web formation on such wires, a looped pickup felt positioned above the cylinder molds and trained around rolls mounted on the frame and located respectively before the first of the aligned cylinder molds and after the last of the aligned cylinder molds, a plurality of turning rolls each within the loop of one of said forming wires, and separate mounting means on said frame for each of said turning rolls for movement of the individual roll to selectively urge the wire associated therewith toward and away from the felt to respectively permit and prevent web transfer from the wire to the felt.

6. A cylinder type paper machine, comprising a frame, a plurality of cylinder molds aligned within the frame, separate looped forming wires for each cylinder mold having the cylinder mold within the loop thereof for effecting web formation on such wires, a looped pickup felt positioned above the cylinder molds and trained around rolls mounted on the frame and located respectively before the first of the aligned cylinder molds and after the last of the aligned cylinder molds, a couch roll positioned above each of said forming wires and within the loop of said felt for directing the felt against each of said forming wires to receive the fibrous web therefrom, means swingably mounting each of said couch rolls on said frame, a plurality of turning rolls each within the loop of one of said forming wires, and separate mounting means on said frame for each of said turning rolls for movement of the individual roll to selectively urge the wire associated therewith toward and away from the felt to respectively permit and prevent web transfer from the wire to the felt.

7. A cylinder type paper machine, comprising a frame, a plurality of cylinder molds aligned within the frame, bearing means mounted on said frame cantileverly supporting each of said cylinder molds at one end thereof,

separate looped forming wires for each cylinder mold having the cylinder mold within the loop thereof for effecting web formation on such wires, a looped pickup felt trained around rolls mounted on the frame and located respectively before the first of the aligned cylinder molds and after the last of the aligned cylinder molds, a plurality of turning rolls each within the loop of one of said forming wires, and separate mounting means on said frame cantileverly supporting each of said turning rolls at the end thereof corresponding to the cantileverly supported cylinder mold end and movable on said frame to selectively urge the wire looping the turning roll toward and away from the felt, said cantilever support means for each cylinder mold and associated turning roll cooperating to permit removal and replacement of the forming wire associated therewith without disturbing the operation of the other cylinder molds aligned therewith.

8. A cylinder type paper machine, comprising a plurality of separate looped forming wires, a cylinder mold within the loop of each of said forming wires for effecting fibrous web formation on the wire, a looped pickup felt having a felt run positioned above the upper run of each of said forming wires to receive the fibrous web therefrom, a turning roll within the loop of each of said forming wires for selectively directing the upper run of each wire against and away from the felt run to respectively permit and prevent web transfer from the wire to the felt, and bearing means cantileverly supporting each cylinder mold and associated turning roll to permit removal and replacement of the forming wire associated therewith without affecting the cooperation between the felt and each of the other forming wires.

9. A cylinder type paper machine, comprising a plurality of separate looped forming wires, a cylinder mold within the loop of each of said forming wires for effecting fibrous web formation on the wire, a looped pickup felt having a felt run positioned above the upper run of each of said forming wires to receive the fibrous web therefrom, a turning roll within the loop of each of said forming wires, means engaging each of said turning rolls to move each roll for selectively directing the upper run of each wire against and away from the felt run to respectively permit and prevent web transfer from the wire to the felt, and bearing means cantileverly supporting each cylinder mold and associated turning roll to permit removal and replacement of the forming wire associated therewith without affecting the cooperation between the felt and each of the other forming wires.

10. A cylinder type paper machine, comprising a plurality of separate looped forming wires, a cylinder mold within the loop of each of said forming wires for effecting fibrous web formation on the wire, a looped pickup felt having a felt run positioned above the upper run of each of said forming wires, a couch roll positioned above each of said forming wires and within the loop of said felt for directing the felt against each of said forming wires to receive the fibrous web therefrom, a turning roll within the loop of each of said forming wires for selectively directing the upper run of each wire against and away from the felt run to respectively permit and prevent web transfer from the wire to the felt, and bearing means cantileverly supporting each cylinder mold and associated turning roll to permit removal and replacement of the forming wire associated therewith without affecting the cooperation between the felt and each of the other forming wires.

11. A cylinder type paper machine, comprising a plurality of aligned pairs of upper and lower couch rolls in nip defining relation, a looped pickup felt passing through all of said nips and enclosing within its loop all of said upper couch rolls, a cylinder mold below said felt associated with each of said lower couch rolls, a separate looped forming wire passing through each of said nips and enclosing within its loop one of said lower couch rolls and the cylinder mold associated therewith for effecting web formation on the wire and transferring the web to the felt at the nip, mounting means for each pair of upper and lower couch rolls, and independent adjusting means cooperating with each of said mounting means to selectively move the pair of rolls in and out of nip defining relation.

5 12. A cylinder type paper machine, comprising a plurality of aligned pairs of upper and lower couch rolls in nip defining relation, a looped pickup felt having a substantially horizontal run passing through all of said nips and enclosing within its loop all of said upper couch rolls, a cylinder mold associated with each of said lower couch rolls and positioned just below the lower couch

10 roll associated therewith, a separate looped forming wire enclosing within its loop each lower couch roll and associated cylinder mold and running upwardly from the cylinder mold and over the lower couch roll, mounting means for each pair of upper and lower couch rolls, and independent adjusting means cooperating with each of said mounting means to selectively move the pair of rolls in and out of nip defining relation.

15 13. A cylinder type paper machine, comprising a plurality of aligned pairs of upper and lower couch rolls in nip defining relation, a looped pickup felt passing through all of said nips and enclosing within its loop all of said upper couch rolls, a cylinder mold associated with each of said lower couch rolls and positioned just below the lower couch roll associated therewith, a separate looped forming wire enclosing within its loop each lower couch roll and associated cylinder mold and running upwardly from the cylinder mold and over the lower couch roll, means swingably mounting each of said upper couch rolls, and adjustable means mounting each of said lower couch rolls movable in both vertical and horizontal directions cooperating with the upper couch roll mounting means to selectively move such rolls in and out of nip defining relation and to alter the angle of the plane of the nip.

20 14. In a cylinder type paper machine, in combination, upper and lower couch rolls in nip defining relation, a looped pickup felt passing through the nip of said couch rolls and enclosing within its loop the upper couch roll, a cylinder mold positioned beneath the lower couch roll, a separate looped forming wire enclosing within its loop the lower couch roll and the cylinder mold and running upwardly from the cylinder mold and over the lower couch roll and through said nip, and adjustable means mounting the lower couch roll movable in both vertical and horizontal directions to selectively move the lower couch roll away from and toward the cylinder mold and in and out of nip defining relation with the upper couch roll.

25 15. In a cylinder type paper machine, in combination, a looped forming wire, a cylinder mold within the loop of said forming wire for effecting fibrous web formation on the wire, a looped pickup felt having a felt run positioned above the upper run of said forming wire to receive the fibrous web therefrom, a turning roll within the loop of said forming wire for selectively directing the upper run of said wire away from and against the felt run to respectively prevent and permit web transfer from the wire to the felt, and bearing means cantileverly supporting the cylinder mold and the turning roll to permit removal and replacement of the forming wire when the turning roll is in a position directing the upper run of the wire away from the felt.

couche rolls and the cylinder mold associated therewith for effecting web formation on the wire and transferring the web to the felt at the nip, mounting means for each pair of upper and lower couche rolls, and independent adjusting means cooperating with each of said mounting means to selectively move the pair of rolls in and out of nip defining relation.

10 12. A cylinder type paper machine, comprising a plurality of aligned pairs of upper and lower couche rolls in nip defining relation, a looped pickup felt having a substantially horizontal run passing through all of said nips and enclosing within its loop all of said upper couche rolls, a cylinder mold associated with each of said lower couche rolls and positioned just below the lower couche

15 roll associated therewith, a separate looped forming wire enclosing within its loop each lower couche roll and associated cylinder mold and running upwardly from the cylinder mold and over the lower couche roll, mounting means for each pair of upper and lower couche rolls, and independent adjusting means cooperating with each of said mounting means to selectively move the pair of rolls in and out of nip defining relation.

20 13. A cylinder type paper machine, comprising a plurality of aligned pairs of upper and lower couche rolls in nip defining relation, a looped pickup felt passing through all of said nips and enclosing within its loop all of said upper couche rolls, a cylinder mold associated with each of said lower couche rolls and positioned just below the lower couche roll associated therewith, a separate looped forming wire enclosing within its loop each lower couche roll and associated cylinder mold and running upwardly from the cylinder mold and over the lower couche roll, means swingably mounting each of said upper couche rolls, and adjustable means mounting each of said lower couche rolls movable in both vertical and horizontal directions cooperating with the upper couche roll mounting means to selectively move such rolls in and out of nip defining relation and to alter the angle of the plane of the nip.

25 14. In a cylinder type paper machine, in combination, upper and lower couche rolls in nip defining relation, a looped pickup felt passing through the nip of said couche rolls and enclosing within its loop the upper couche roll, a cylinder mold positioned beneath the lower couche roll, a separate looped forming wire enclosing within its loop the lower couche roll and the cylinder mold and running upwardly from the cylinder mold and over the lower couche roll and through said nip, and adjustable means mounting the lower couche roll movable in both vertical and horizontal directions to selectively move the lower couche roll away from and toward the cylinder mold and in and out of nip defining relation with the upper couche roll.
